US00D585063S

(12) **United States Design Patent**
Hargreaves et al.

(10) **Patent No.:** **US D585,063 S**
(45) **Date of Patent:** **** Jan. 20, 2009**

(54) **KEYBOARD**

(75) Inventors: **William Hargreaves**, Bellevue, WA (US); **Drew Carlson**, Seattle, WA (US); **Mark Ando**, Seattle, WA (US); **Jerry Yamamoto**, Seattle, WA (US); **Jon Biggs**, Lake Forest Park, WA (US); **Carsten Buus**, Snohomish, WA (US)

(73) Assignee: **Kinesis Corporation**, Bothell, WA (US)

(**) Term: **14 Years**

(21) Appl. No.: **29/298,046**

(22) Filed: **Nov. 27, 2007**

(51) **LOC (9) Cl.** **14-02**

(52) **U.S. Cl.** **D14/393**

(58) **Field of Classification Search** ..... D14/391-399; D18/1, 2, 6, 7; 200/5 A, 5 R, 6 A, 6 R; 235/145 A, 235/145 R; 178/17 A, 17 C; 341/22, 23; 345/160, 168, 169; 400/484-486, 488, 489, 400/492; 361/680-686

See application file for complete search history.

CLAIM

The ornamental design for a keyboard, as shown and described.

DESCRIPTION

FIG. 1 is a front perspective view of a keyboard showing our new design.

FIG. 2 is a top plan view thereof.

FIG. 3 is a bottom plan view thereof.

FIG. 4 is a front elevation view thereof.

FIG. 5 is a rear elevation view thereof.

FIG. 6 is a left side elevation view thereof; and,

FIG. 7 is a right side elevation view thereof.

The elements illustrated in broken lines in the drawing figures are considered environmental only and do not form a part of the claimed design.

1 Claim, 5 Drawing Sheets
